(57) **CLAIM**

The ornamental design for a work vehicle body, as shown and described.

DESCRIPTION

FIG. 1 is a perspective view of a work vehicle body according to our new design;

FIG. 2 is an enlarged and truncated perspective view thereof;

FIG. 3 is a first side elevation view thereof;

FIG. 4 is a second side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is an enlarged detail view of an area of FIG. 2; and,

FIG. 10 is an enlarged sectional view taken along plane

10-10 of FIG. 9.

FIGS. 1-10 illustrate the work vehicle body design on a right side of an example work vehicle when viewed from the perspective of FIG. 1. The work vehicle body design may be on the left side of a work vehicle and will be understood to be viewed as mirror images of the views shown in FIGS. 1-10.

The broken lines shown in the views depict environmental subject matter only and form no part of the claimed design.

(Continued)

The dot-dash broken lines in FIGS. 2 and 9 represent boundaries of the enlarged portions and form no part of the claimed design.
